UNITED STATES PATENT OFFICE.

JOHN H. HART, OF TACOMA, WASHINGTON.

CARTRIDGE-CLEANING APPARATUS.

No. 827,866.

Specification of Letters Patent.

Patented Aug. 7, 1906.

Application filed January 22, 1906. Serial No. 287,223.

To all whom it may concern:

Be it known that I, JOHN H. HART, a citizen of the United States of America, residing at Tacoma, in the county of Pierce and State of Washington, have invented certain new and useful Improvements in Cartridge-Cleaning Apparatus, of which the following is a specification, reference being had therein to the accompanying drawings.

10 This invention relates to devices for cleaning cartridge-shells, and has for its objects to clean a number of shells at the same time and to hold the cartridges in their proper position while being cleaned. I attain these objects 15 by the mechanism illustrated in the accompanying drawings, in which—

Figure 1 is a plan of my device. Fig. 2 is an end view thereof. Fig. 3 is a side view of the mechanism. Fig. 4 is a side view of the 20 cartridge-holder, showing it partly opened; and Fig. 5 is a plan of a part thereof, showing one cartridge-shell in place.

Similar numerals of reference refer to similar parts throughout the several views.

25 My invention consists of a frame 1, provided with jaws 2, by means of which it is clamped with the screw 3 to any convenient table. The frame 1 extends upward from the jaws 2 a convenient distance to a boss 4 and then bends at right angles to form the horizontal arm 5, which extends over the table to which the frame is fastened. Referring to Fig. 1, it will be seen that a bar 6 is secured to the end of the arm 5, lying directly 30 back of said arm and being separated therefrom by a small space, the parts 5 and 6 being suitably grooved or dovetailed at their ends, as shown in Fig. 2, to insure their alignment at all times and are pulled together 40 through this dovetailed joint by a suitable bolt 7.

A driving gear-wheel 8 is mounted on a pin 9, which is secured in the boss 4 above mentioned and has an operating-handle 10 secured to it. This gear 8 gears with the train of similar smaller gears 11, which are mounted between the arm 5 and the bar 6. These gears 11 are provided on one side with a small bearing-shaft 12, which engages in 50 suitable holes in the bar 6, and on the other side with bearing-shafts 13 of larger diameter, which engage in larger holes in the arm 5. Extending out from these large bearings 13 are the brush-shafts 14, on which are 55 mounted any suitable cleaning or scouring device, (indicated in the drawings as the

brushes 15.) It will be seen that if it is desired to remove, for any cause, any of the scouring-brushes 15 it is only necessary to unscrew the bolt 7, remove the bar 6, and then the gears 11 are all free to be removed from the arm 5, and since the holes in the arm 5 are of large diameter the brushes 15 will pass freely through them. Should it not be desired to use brushes, these may be replaced 65 by any cleaning or scouring means, such as a cloth, a sponge, or other device.

The cartridges are held at their proper distances apart in the cartridge-holder, which consists of two blocks of wood or other material 16 and 17, hinged together and having formed in their adjacent surfaces semicylindrical recesses 18, into which the cartridge-shells will fit and be clamped between the said blocks. These blocks 16 and 17 are also 70 provided with a suitable latching device consisting of a pivoted hook 19, secured to the block 17, and a nail or button 20, secured to the block 16, so that when the recesses 18 have been filled with cartridges and the 80 blocks brought together and the hook 19 engages the button 20 then the cartridges within the recesses will be clamped between the blocks 16 and 17, and since the recesses 18 are spaced to correspond with the spacing 85 of the shafts 14 the cartridge-shells therein will fit over the brushes when they are applied thereto.

Having now described my invention, what I claim is—

1. In a cartridge-cleaning apparatus, the combination of a frame, a driving gear-wheel mounted thereon, an arm extending from said frame, a removable back bar secured to the end of said arm, a train of driven gears 95 mounted between said arm and said back bar and gearing with said driving gear-wheel, and cleaning-brushes secured to said driven gears and adapted to clean the inside of cartridge-shells.

2. In a cartridge-cleaning apparatus, the combination of a frame, a driving gear-wheel mounted thereon, an arm extending from said frame and having large bearing-holes therein, a removable back bar secured to the 105 end of said arm and having smaller bearing-holes therein, a train of driven gears mounted between said arm and said back bar in the bearing-holes therein and gearing with said driving gear-wheel, and cleaning-brushes secured to said driven gears and adapted to 110 clean the inside of cartridge-shells.

3. In a cartridge-cleaning apparatus, a frame having a driving-gear mounted thereon, an arm extending from said frame, a removable back bar secured to the end of said arm, a train of driven gears mounted between said arm and said back bar and gearing with said driving gear-wheel, and cleaning-brushes secured to and extending from said driving-gears; in combination with a clamp having recesses therein adapted to

hold cartridge-shells in such position that each shell may be brought simultaneously in cleaning contact with the corresponding rotating brush.

In testimony whereof I affix my signature 15 in presence of two witnesses.

JOHN H. HART.
